UNITED STATES PATENT OFFICE

2,530,820

DUAL IDLER PHONOGRAPH DRIVE

John J. Hoehn and Arthur G. Zimmerman, Indianapolis, Ind., assignors to Radio Corporation of America, a corporation of Delaware

Original application July 31, 1940, Serial No. 348,860. Divided and this application January 29, 1944, Serial No. 520,152

5 Claims. (Cl. 74—190)

1

This invention relates to phonographic apparatus of the type adapted to record sound upon a blank disc for immediate play-back, and more particularly to the turntable driving mechanism thereof, the present invention being in the nature of an improvement over those disclosed and claimed in the Brady and Weathers Patent No. 2,260,289 and the Hoehn Patent No. 2,260,319, and the present application being a division of our copending application Serial No. 348,860, filed July 31, 1940, now Patent No. 2,350,682, granted June 6, 1945 and assigned to Radio Corporation of America.

In the aforesaid Brady and Weathers patent, there is disclosed a phonograph turntable driving mechanism comprising a driving motor the shaft of which is formed with two pulleys or driving surfaces of different diameters employed for driving the turntable at one or another of two speeds by means of an interposed friction idler. This driving mechanism constitutes a part of a phonographic apparatus which may be used either for recording sound on a blank disc or playing back the recorded disc. While satisfactory in many respects, this driving mechanism is subject to certain inherent limitations which are overcome by the driving mechanism shown in the Hoehn patent, identified above. According to the latter, the same type of driving motor with stepped pulley is employed as is disclosed in the Brady and Weathers patent, but instead of using merely one idler, two friction idlers are employed between the driving motor shaft and the turntable. With respect to the motor shaft, the second friction wheel employed by Hoehn is arranged symmetrically opposite to the single friction wheel shown by Brady and Weathers. In this way, the transmitted load is divided between the two friction wheels or idler pulleys. A single control lever which is common to both of the friction idler supporting arms is arranged to operate said arms in order to either move them away from or move them into torque transmitting position.

While the Hoehn arrangement offers certain distinct advantages over that proposed by Brady and Weathers, it has been found, in some cases, that inaccuracies in the driving shaft of the single motor employed and slight irregularities in motor speed may be transmitted to the turntable, since both friction idlers operate from the same motor. Moreover, in arrangements such as shown in both of the above identified patents, when the motors are shut off and the friction idlers are simultaneously removed from

2

engagement with the flange on the turntable periphery, the turntable continues to coast awhile and thus some of the record area is caused to be used up needlessly.

5 The primary object of our present invention is to provide an improved phonograph turntable drive which will not be subject to the aforementioned limitations.

More particularly, it is an object of our present invention to provide an improved turntable driving mechanism as aforesaid by means of which a more constant speed of the turntable can be achieved than was possible heretofore.

Another object of our present invention is to 15 provide an improved turntable driving mechanism of the type set forth above wherein the turntable may not only be driven very constantly or uniformly at any one of the plurality of different speeds, but wherein the turntable 20 can be brought to a quick stop when the motor power is disconnected therefrom.

Still another object of our present invention is to provide an improved phonograph turntable driving mechanism employing a pair of discrete 25 motors so arranged that the failure of either one of them will not render the driving mechanism inoperative.

It is also an object of our present invention to provide an improved turntable driving mechanism as above set forth which is relatively simple 30 in construction and highly efficient in use.

In accordance with our present invention, we employ two separate or discrete driving motors spaced somewhat circumferentially around the 35 turntable and each provided with a pair of stepped pulleys on its driving shaft arranged to drive the turntable at one or another of two different speeds. Coupling to the turntable is attained through a pair of discrete, floatingly-mounted, friction idlers, each associated with a 40 separate one of the motors. In effect, therefore, the turntable is driven at two circumferentially spaced points on the periphery thereof by two motors which are connected in parallel 45 relation to a common power source. Thus, the failure of one motor still permits the second motor to drive the turntable.

The chief advantage in employing two motors 50 as above described is that any slight irregularities that may exist in the drive provided by one will be overcome by the uniform drive of the other, since it is most unlikely that both motors will be subject to the same kind of irregularities at the same points. Consequently, 55 a more uniform drive is provided for the turn-

table than when a single motor is employed, regardless of whether a single friction idler or a pair of friction idlers may cooperate therewith to transmit torque from the single motor to the turntable, as in the above identified patents.

In the arrangement of our present invention, a common control arm is employed for simultaneously coupling and uncoupling the two idler wheels to their respective motors and to the turntable. This common control also operates a brake device associated with the turntable, the arrangement being such that when the friction idlers are disconnected from their respective motors, the brake is immediately applied to the turntable to stop rotation thereof substantially instantaneously.

The novel features that we consider characteristic of our invention are set forth with particularity in the appended claims. The invention itself, however, both as to its organization and method of operation, as well as additional objects and advantages thereof, will best be understood from the following description of one embodiment thereof when read in connection with the accompanying drawings, in which

Figure 1 is a top plan view of a recording apparatus according to our present invention, and

Figure 2 is an enlarged side elevation of the turntable driving mechanism.

Referring more particularly to the drawings, wherein similar reference characters designate corresponding parts throughout, there is shown a motor board 1 carrying a frame member 2 provided with a bushing 3 in which is journaled a turntable shaft 4 terminating in a tapered spindle 5 on which is mounted a turntable 6, the turntable constituting a supporting means for a record disc or blank R. The turntable 6 is driven from a pair of motors 7, each of which includes a motor shaft formed with a relatively small diameter 7a at its upper extremity and a relatively large diameter 7b immediately below the portion 7a. In each case, the motor may be coupled to the periphery of the turntable 6 by means of a rubber tired idler 8 which is floatingly carried on an arm 9, each arm 9 being pivotally mounted on a lever 10 which, in turn, is pivoted on a post 11, a coil spring 12 around each of the posts 11 constantly urging the associated lever 10 to an elevated position. The motors 7 and the friction idlers 8 are so arranged that they are spaced circumferentially around the turntable.

When the lever 10 is in the elevated position shown in Fig. 2, the friction idlers 8 may be brought into engagement with the smaller diameter portion 7a of the motor shaft and the periphery of the turntable to drive the turntable at a relatively slow speed, for example, 33 1/3 R. P. M.; and when the lever 10 is depressed against the action of the spring 12 to a point where the friction idler 8 is on the level of the larger diameter portion 7b of the motor shaft, and the friction wheel 8 is then brought into engagement with the shaft portion 7b and the turntable periphery, the turntable will be driven at a relatively higher speed, for example, 78 R. P. M. This particular driving mechanism constitutes the subject matter of the above mentioned Brady and Weathers patent and is therein disclosed and claimed in greater detail.

For adjustment of the levers 10 on their respective posts 11, we provide a post 13 on a motor plate 14 which is carried by the motor board 1 and, in turn, carries the motors 7, and we slidably and rotatably mount a sleeve 15 on the post

13. The sleeve 15 is provided with a bayonet slot 16 through which a pin 17 on the post 13 extends, the sleeve 15 being also provided with a pair of oppositely extending arms 18 which are bifurcated at their ends to receive the upper ends of the posts 11 and against which the springs 12 hold the upper ends of the collars 19 formed on the levers 10. With the sleeve 15 in the position shown in Fig. 2, wherein the pin 17 is in the vertical portion of the bayonet slot 16, the springs 12 are free to elevate the levers 10 to a position wherein the friction idlers 8 are in alignment with the smaller diameter motor shaft portions 7a. On the other hand, by depressing the sleeve 15 on the post 13 until the horizontal portion of the bayonet slot 16 engages the pin 17, the levers 10 are forced down against the action of the springs 12 to bring the idler wheels 8 in alignment with the larger diameter motor shaft portions 7b. The sleeve 15 may be locked in the latter position by simply turning it slightly in a clockwise direction (looking down from the top) to cause the portion 16a of the bayonet slot 16 to embrace the pin 17. A pair of coil springs 20 each fixed at one end to the motor plate 14 and at its other end to a downwardly extending lug on the respective arms 9 constantly urges each of the associated idlers into engagement with the motor shafts and the turntable.

30 To enable disconnecting the idler wheels 8 from their respective motor shafts and the turntable, a lever 21 is pivoted on the post 13 and has fixed at its ends a pair of upstanding pins 22 received in slots formed in the ends of a pair of levers 23 and 23a, each pivotally mounted on a separate one of the posts 11. The lever 23 is provided with an upstanding member 24 which is arranged to engage the associated lever 10, and the lever 23a is provided with a similar upstanding member 24a which is arranged to engage its associated lever 10, the lever 23a being also provided with an operating handle 25. By moving the handle 25 in a counterclockwise direction, as viewed in Fig. 1, the lever 23a moves with it in a counterclockwise direction to bring its member 24a into engagement with the associated lever 10 and cause the latter to move in a counterclockwise direction about the shaft 11 to force the friction idler 8 out of engagement with the associated motor shaft and the turntable against the action of the connected spring 20. At the same time, counterclockwise movement of the lever 23a effects clockwise movement of the lever 21 on the post 13, and this, in turn, effects counterclockwise movement of the lever 23 and the left-hand lever 10 to bring its associated friction idler 8 out of engagement with the associated motor shaft and the turntable. Once the idlers 8 have been uncoupled from the respective motors and the turntable, the sleeve 15 may be adjusted on the post 13 to bring the idlers to the level of either the motor shaft portion 7a or the motor shaft portion 7b in the manner heretofore described, after which the operating handle 25 is moved in the opposite direction from that previously indicated whereupon the reverse action from that heretofore described takes place and the springs 20 pull their respective idlers 8 into engagement with the motor shafts and the turntable periphery.

Fixed to the motor board 1 in proximity to the turntable 6 is a bracket 26 which carries a spring blade 27 having a friction lining 28 secured thereto. An arm 29 is adjustably mounted on the lever 23a and extends laterally from the lever

23a toward the spring blade 27, there being a suitable clearance between the spring 27 and the adjacent end of the arm 29. When the lever 23a is turned in a counterclockwise direction, as viewed in Fig. 1, to disconnect the idlers 8 from the motors 7 and the turntables 6, the right-hand end of the arm 29 will engage the free end of the blade 27 and press the brake lining against the turntable periphery to bring the turntable to a quick stop. This is very desirable, in many instances, since the turntable is very massive and would otherwise continue to rotate for a considerable period.

From the foregoing description, it will undoubtedly be apparent to those skilled in the art that we have provided an improved turntable drive which will insure a more constant or uniform drive for the turntable than was attainable with drives heretofore employed. At the same time, the control mechanism for our improved drive is so arranged that the turntable is brought to a quick stop once the friction idlers are disconnected therefrom.

Although we have shown and described but one embodiment of our invention, it will be apparent to those skilled in the art that many other modifications thereof, as well as various changes in the particular one described, are possible within the spirit of our invention. We, therefore, desire that our invention shall not be limited except insofar as is made necessary by the prior art and by the spirit of the appended claims.

We claim as our invention:

1. In phonographic apparatus including a turntable, mechanism for driving said turntable comprising a plurality of discrete driving members, said members being spaced from each other circumferentially about said turntable, a like plurality of friction idler wheels each associated with a separate one of said driving members, said idler wheels being each movably mounted for movement into and out of power transmitting position between their respective driving members and said turntable, and control means common to all of said idler wheels for simultaneously effecting movement of all said idler wheels into one or the other of said positions.

2. In phonographic apparatus including a turntable, mechanism for driving said turntable comprising a plurality of discrete motors, said motors being spaced from each other circumferentially about said turntable, a like plurality of friction idler wheels each associated with a separate one of said motors, said idler wheels being each movably mounted for movement into and out of power transmitting position between their respective motors and said turntable, and control means common to all of said idler wheels for simultaneously effecting movement of all said idler wheels into one or the other of said positions.

3. In phonographic apparatus including a turntable, mechanism for driving said turntable comprising a pair of motors spaced from each other circumferentially about said turntable, each of said motors having a shaft provided with driving portions of different diameters, a pair of friction idlers each associated with a separate one of said motors and mounted for movement into engagement with any preselected one of their respectively associated shaft portions whereby to effect driving of said turntable at any preselected one of a plurality of speeds, said idlers being also movably mounted for movement into engagement with said turntable and said preselected shaft

portions for transferring power from their respective motors to said turntable, and means including a common control member for moving both said idlers simultaneously into engagement with said turntable and the selected portions of their said respectively associated shaft portions at will.

4. In phonographic apparatus including a turntable, mechanism for controlling rotation of said turntable comprising a plurality of discrete motors for driving said turntable, said motors being spaced from each other circumferentially about said turntable, a like plurality of friction idler wheels each associated with a separate one of said motors, said idler wheels being each movably mounted for movement into and out of power transmitting position between their respective motors and said turntable, control means common to all of said idler wheels for simultaneously effecting movement of all said idler wheels into one or the other of said positions, a brake device associated with said turntable, and means associated with said control means for applying said brake device to said turntable when said control means is operated to effect movement of said idler wheels out of said power transmitting position.

5. In phonographic apparatus including a turntable, mechanism for controlling rotation of said turntable comprising a pair of motors spaced from each other circumferentially about said turntable, each of said motors having a shaft provided with driving portions of different diameters, a pair of friction idlers each associated with a separate one of said motors and mounted for movement into engagement with any preselected one of their respectively associated shaft portions whereby to effect driving of said turntable at any preselected one of a plurality of speeds, said idlers being also movably mounted for movement into engagement with said turntable and said preselected shaft portions for transferring power from their respective motors to said turntable, means including a common control member for moving both said idlers simultaneously into engagement with said turntable and the selected portions of their said respectively associated shaft portions at will, a brake device associated with said turntable, and means associated with said control member for applying said brake device to said turntable when said control member is operated to effect movement of said idler wheels out of said power transmitting position.
